UNITED STATES PATENT OFFICE.

WILLIAM C. BAXTER, OF BEVERLY, MASSACHUSETTS, ASSIGNOR TO UNITED SHOE MACHINERY CORPORATION, OF PATERSON, NEW JERSEY, A CORPORATION OF NEW JERSEY.

SOLE-LEVELING MACHINE.

Application filed October 27, 1920. Serial No. 419,842.

To all whom it may concern:

Be it known that I, WILLIAM C. BAXTER, a citizen of the United States, residing at Beverly, in the county of Essex and State of Massachusetts, have invented certain new and useful Improvements in Sole-Leveling Machines; and I do hereby declare the following to be a full, clear, and exact description of the invention, such as will enable others skilled in the art to which it appertains to make and use the same.

The present invention relates to machines for operating upon the soles of boots and shoes, and more particularly to sole leveling machines of the type provided with a leveling roll and a shoe supporting jack which is oscillated beneath the leveling roll, the roll being urged by a spring toward the jack to apply pressure to the sole of a shoe supported on the jack. In sole leveling machines of this type at present in general commercial use, the pressure of the leveling roll varies at different portions of the sole, due to variations in the height of the sole, this variation in pressure being most pronounced when the machine is operating upon women's shoes having the so-called cottage shank with a peaked ball line. In fact with this type of shoe, in order to avoid excessive pressure at the ball line which might break down and injure the sole, it is necessary to so adjust the pressure applying spring that the pressure on the remaining portions of the sole is generally too light. In the patent to Winkley, No. 610,314, dated September 26, 1898, a mechanism is illustrated and described which is designed to overcome such objectionable variation in the pressure applied by the leveling roll on the different portions of a sole by adjusting or varying automatically the tension of the pressure applying spring during a cycle of operations of the machine to compensate for the variations in the height of the sole, so that a substantially uniform pressure may be applied throughout the portion of the sole acted upon by the leveling device. In a mechanism, however, constructed in accordance with said patent, the degree or amount of such automatic adjustments of the pressure applying springs for each complete cycle is constant irrespective of the type of shoe being operated upon, so that while such a mechanism is capable of properly regulating the pressure applied on one type of shoe,

it is not capable of properly regulating the pressure applied on different types of shoes such as men's and women's shoes having ball lines of considerably different heights.

Accordingly, an object of the present invention is to provide means in a sole leveling machine for properly regulating the pressure applied on the sole of a shoe during the leveling operation irrespective of the type of shoe being operated upon.

With this object in view, a feature of the present invention contemplates the provision in a sole leveling machine having a sole leveling device, a shoe supporting jack, and mechanism comprising pressure applying means for relatively actuating the leveling device and jack to level the sole of a shoe supported on the jack, of mechanism acting automatically to adjust said pressure applying means to regulate the pressure applied on the sole, said automatic mechanism having provision for adjustment to regulate the range of pressure provided by such adjustment of said pressure applying means. Such provision for adjustment of said automatic mechanism preferably enables the pressure applying means to be so controlled as to apply a substantially uniform pressure on the different portions of the sole of a shoe that are acted upon by the leveling device irrespective of the type of shoe being operated upon.

A sole leveling machine of the type to which the present invention particularly relates is usually provided with two shoe-supporting jacks and sole leveling rolls, a separate pressure-applying spring being associated with each jack and roll. In the machine disclosed in said patent to Winkley, the mechanism for automatically varying the tension of the pressure-applying springs to regulate the pressure applied on the soles, as above described, comprises a separate cam and connections for each spring, which duplication of parts results in the mechanism being more or less complicated, and, moreover, this mechanism has not been found to be entirely satisfactory in operation.

Accordingly, another object of the present invention is to simplify and improve the construction and mode of operation of the mechanism, in sole leveling machines, for regulating the pressure applied to a sole during the leveling operation.

With this object in view, a feature of the present invention contemplates the provision in a sole leveling machine having a plurality of shoe-supporting jacks and cooperating leveling rolls relatively movable to cause a roll to travel over the sole of a shoe supported on a jack, and having pressure-applying mechanism, of a single cam and suitable connections for regulating, during the operation of the machine, the pressure applied by each roll to the sole of a shoe. This mechanism for regulating the pressure applied to a sole, as at present constructed, not only does away with the duplication of parts of said patented construction, but also is certain and reliable in operation. Except as defined in the claims, however, the features of the invention are not limited to a machine employing a plurality of shoe supporting jacks and leveling rolls.

Other features of the invention consist in certain constructions, arrangements and combinations of parts hereinafter described and claimed, the advantages of which will be obvious to those skilled in the art.

The several features of the invention will be clearly understood from the following description and accompanying drawings, in which:—

Figure 1 is a side elevation of a sole leveling machine embodying the features in their preferred form; Fig. 2 is a detail side elevation, partly in section, of the leveling roll and its carrier and the mechanism for regulating the pressure of the leveling roll; and Fig. 3 is a sectional elevation, with certain parts removed, taken on the line 3—3 of Fig. 2.

The machine illustrated in the drawings is provided with a pair of shoe supporting jacks 2, and a pair of vibrating leveling rolls 4. The shoe supporting jacks 2 are pivotally mounted at 6 on the frame of the machine and when thrown into operative position are oscillated either in unison or alternately, as desired, beneath the leveling rolls through connection with cams carried by the main cam shaft 8 of the machine. The pair of vibrating leveling rolls 4 are mounted on independent carriers 12 which in turn are mounted on carrier beds 14 which are fulcrumed at 16 on the machine frame. The leveling rolls 4 are independently urged downwardly to apply pressure to the soles of the shoes supported on the jacks by means of coiled springs 18 which bear at their lower ends on the forward portion of pressure levers 20 having their rear ends fulcrumed on the frame and their forward ends connected by links 22 with the carrier beds 14. Manually operable means is provided for separately varying the tension of the springs 18 to vary the amount of pressure applied on the soles.

The parts above described may be and

preferably are the same, except as herein-after described, as the corresponding parts of the machine illustrated and described in the patent to Baxter No. 1,208,895, dated September 19, 1916, to which reference may be had for a full and complete description of these and other parts of the machine not fully described herein.

Also, as in Baxter's patented machine, in the machine illustrated in the drawings, the manually operable means for separately varying the tension of the coiled springs 18 to vary the amount of pressure applied on the soles comprises abutment blocks 24 for the upper ends of the springs 18, which blocks are mounted on the lower ends of adjusting screws 26 mounted in bearings 28. The bearings 28 constitute extensions of the upper ends of casings 30 that enclose the springs, and the bearings and casings are formed on brackets 31 secured to the frame. A hand wheel 32 is secured to the upper end of each screw 26 for turning the screw to vary the tension of a spring 18.

The illustrated machine is also provided with means comprising a single cam and suitable connections for simultaneously adjusting the tension of both of the coiled springs 18 to regulate the pressure applied by the leveling rolls on the soles during a cycle of operations, so as to compensate for variations in the heights of different portions of each sole that is operated upon. To this end, the screws 26 are axially threaded through sleeves 33 which are mounted for longitudinal movement in the bearings 28 and their longitudinal positions are controlled to regulate the tensions of the springs 18 by a single cam 34 carried by the main cam shaft 8. The connection between the sleeves 33 and the cam 34 comprises a pair of arms 36 secured to a rock shaft 38 having its ends journaled in bearings at the upper ends of the brackets 31. The free ends of the arms 36 are forked to engage shoulders 40 formed on the sleeves. To prevent the sleeves from turning in their bearings the portions of the sides thereof that engage the forked ends of the arms 36 are flattened. An actuating arm 42 is secured to the rock shaft 38 substantially midway between its ends. A link 44 is pivotally connected at one end with the free end of the arm 42 and is pivotally connected at its other end with a pin 46 which, as shown in full lines in Fig. 2, is secured in an aperture in the forward end of an arm 48 having its rear end pivotally mounted on a shaft 50 which is mounted at its ends in the brackets 31. The upper end of a link 52 is pivotally connected with the arm 48 between its ends, and the lower end of the link 52 is forked to embrace the cam shaft 8 and is provided with a cam roll 54 that engages the periphery of the cam 34.

With this construction it will be apparent, that, as the sole of the shoe is acted upon at the ball line by a leveling roll, as shown in full lines in Fig. 2, one of a series of depressions 56 of the cam 34 will engage the cam roll 54 to raise the spring abutments 24, that, as the forepart of the sole is acted upon by the leveling roll, one of two raised portions 58 of the cam will engage the cam roll to depress the spring abutments 24, the maximum amount. The distances that the spring abutments 24 are thus raised and lowered correspond substantially to the variations in the heights of the different portions of the soles of the shoes being operated upon, so that the tension of the pressure applying springs remain substantially constant during the leveling operation irrespective of variations in the heights of different portions of the soles, resulting in the leveling rolls applying a substantially uniform pressure throughout the portion of the soles acted upon. It may, however, be desirable in some cases to vary the pressure applied by the leveling rolls upon certain portions of the sole, and this obviously may be accomplished by changing the design of the cam 34.

The illustrated machine has provision for varying the degree of adjustment of the pressure applying springs 18 by the action 35 of the cam 34 so that the pressure exerted by the leveling rolls during a cycle of operations may be properly regulated for both men's and women's shoes having ball lines of different heights. To this end the pivotal 40 connection of the link 44 with the arm 48 is adapted to be changed from a position at the forward end of the arm, as shown by full lines in Fig. 2, to a position nearer the rock shaft 50, herein shown as between the 45 rock shaft 50 and the pivotal connection between the arm 48 and the cam actuated link 52. As shown by broken lines in this figure, the pivot pin 46 for the link is adapted to be removed from the forward end of the 50 arm 48 and secured in an aperture 62 in the arm. It will be apparent that when the pivotal connection between the link 44 and arm 48 is located at the forward end of the arm there will be a maximum amount of variation 55 in the pressure exerted by the leveling rolls on the soles during a cycle of operations, so that such adjustment of the link particularly adapts the machine to operate upon shoes having a high ball line. When 60 the pivotal connection between the link 44 and the arm 48 is adjusted to the position indicated by broken lines in Fig. 2, the degree of variation in the pressure exerted by the rolls during a cycle of operations will be 65 decreased, thereby particularly adapting the

machine to operate upon shoes having a low ball line.

The variation in pressure accomplished by the machine may perhaps be more clearly understood if expressed analytically. The 70 force exerted by the spring is proportional to the amount it has been shortened from its normal full length, which we will call L . Let us represent by L^1 its length when the rolls 54 are at the lowest point of the cam 58. L^1 is variable by the handle 32. The cam produces a cyclic variation in the length, such variation being arithmetic rather than geometric—that is, additive (or subtractive) rather than multiplicative. According to the 80 illustrated construction, this variation is a certain number of inches of shortening at any instant, irrespective of the value of L^1 . We may call it $f(t)$, a function of the time measured from the beginning of an operation. The force of the spring in the Winkley machine of Patent No. 610,314 may therefore be represented by

$$L - L^1 + f(t)$$

90

where L^1 is variable by the handle and $f(t)$ is a cyclic variable defining the cam. In the machine of the present invention the adjustment of the link 44 in effect multiplies the action of the cam by a constant so that 95 the force exerted by the spring may be represented by

$$L - L^1 + A \cdot f(t).$$

In the preceding discussion it has been tacitly assumed that the link 20 did not move, whereas some change in the length of the spring actually results from its movement. This change is relatively small, and is likewise a cyclic function of the time. We may 105 call it $F(t)$ and represent the force exerted by the spring as

$$L - L^1 + F(t) + A \cdot f(t).$$

Here the changes in length introduced by 110 the variations in $L - L^1$ and by $F(t)$ can be made small in comparison to $A \cdot f(t)$, so that the range of variation in pressure is itself variable over far wider limits by the aid of the present invention than it was under 115 prior practice. Also it should be noticed that the varying of $L - L^1$ by the handle, which could be produced in the Winkley machine, as well as in the herein illustrated one, effects no change in range of pressure at 120 all, but only shifts the whole range of pressure along the scale. With the machine of the present invention the range can be altered within wide limits without changing the minimum pressure at all, and in addition, the variations secured by prior machines are available, if desired.

While the features described above are well adapted for use in a sole leveling machine of the type illustrated in the drawings, 130

it is to be understood that, except as defined in the claims, certain features of the invention are not limited to use in a sole leveling machine of this type.

5 The nature and scope of the present invention having been indicated and a machine embodying the several features of the invention in their preferred form having been specifically described, what is claimed is:—

- 10 1. A sole leveling machine having, in combination, a plurality of shoe supporting jacks and cooperating leveling rolls relatively movable to cause a roll to travel over the sole of a shoe supported on a jack, pressure applying mechanism, and a single cam and suitable connections for regulating, during the operation of the machine, the pressure applied by each roll to the sole of a shoe.
- 15 2. A sole leveling machine having, in combination, a plurality of shoe supporting jacks and cooperating leveling rolls relatively movable to cause a roll to travel over the sole of a shoe supported on a jack, pressure applying mechanism associated with each jack and roll, and a single cam and suitable connections for regulating, during the operation of the machine, the action of all of said pressure applying mechanisms.
- 20 3. A sole leveling machine having, in combination, a plurality of shoe supporting jacks and cooperating leveling rolls relatively movable to cause a roll to travel over the sole of a shoe supported on a jack, a pressure applying spring associated with each jack and roll, a single cam, and means actuated by the cam for regulating the tension of all of the springs during the operation of the machine.
- 25 4. A sole leveling machine having, in combination, a plurality of shoe supporting jacks and cooperating leveling rolls relatively movable to cause a roll to travel over the sole of a shoe supported on a jack, a pressure applying spring associated with each jack and roll, a rock shaft, and means actuated by the rock shaft for simultaneously regulating the tension of all of the springs during the operation of the machine.
- 30 5. A sole leveling machine having, in combination, a sole leveling roll and a shoe supporting jack relatively movable to cause the roll to travel over the sole of a shoe supported on the jack, pressure applying means and mechanism acting automatically to adjust said pressure applying means to regulate the pressure applied on the sole, said automatic mechanism being constructed and arranged for adjustment to regulate the degree of such adjustment of said pressure applying means.
- 35 6. A sole leveling machine having, in combination, a plurality of shoe supporting jacks and cooperating leveling rolls relatively movable to cause a roll to travel over

the sole of a shoe supported on a jack, a pressure applying device associated with each jack and roll, and mechanism acting automatically to adjust simultaneously said pressure applying devices to regulate the pressure applied on the soles, said automatic mechanism being constructed and arranged for adjustment to regulate the degree of such adjustments of said pressure applying devices.

7. A sole leveling machine having, in combination, a sole leveling roll and a shoe supporting jack, relatively movable to cause the roll to travel over the sole of a shoe supported on the jack, a pressure applying spring, and mechanism acting automatically to adjust the tension of said spring during a cycle of operations of the machine, said mechanism being constructed and arranged for adjustment to vary the degree of such adjustment of the spring.

8. A sole leveling machine having, in combination, a sole leveling roll, a shoe supporting jack, means for relatively actuating the leveling roll and jack to level the sole of a shoe supported on the jack comprising a roll, a pressure lever, a link connecting one end of the lever and the roll, a spring connected with the lever and arranged to press the roll into engagement with the sole of a shoe supported on the jack, and means acting automatically during the operation of the machine to vary the tension of said spring, said means being constructed and arranged for adjustment to vary the range of the said variation of the tension.

9. A sole leveling machine having, in combination, a sole leveling device, a shoe supporting jack, means for pressing the leveling device into engagement with the sole of a shoe supported on the jack comprising a pressure applying lever, connections between the lever and said device, a spring having one end engaging the lever, an abutment for the other end of the spring, and means acting automatically during the operation of the machine to adjust the abutment to regulate the tension of the spring.

10. A sole leveling machine having, in combination, a shoe supporting jack, a sole leveling device, means for relatively actuating the jack and leveling device to level the sole of a shoe supported on the jack comprising a pressure applying spring, a sleeve longitudinally movable, a screw axially threaded through the sleeve, an abutment on one end of the screw for one end of the spring, means for turning the screw to vary the tension of the spring, and means for moving the sleeve longitudinally to vary the tension of the spring.

11. A sole leveling machine having, in combination, a shoe supporting jack, a sole leveling device, and mechanism comprising pressure applying means for relatively actu-

- 10 12. A sole leveling machine having, in combination, a shoe supporting jack, a sole leveling device, and mechanism comprising a variable-pressure applying means for relatively actuating the jack and leveling device to level the sole of a shoe supported on the jack, said variable-pressure applying means

being constructed and arranged for adjustment to adapt the range of variation of the pressure to the needs of the shoe being leveled.

13. A sole leveling machine having, in combination, a shoe supporting jack, a sole leveling device, and mechanism comprising a variable-pressure applying means for relatively actuating the jack and leveling device to level the sole of a shoe supported on the jack, said variable-pressure applying means being constructed and arranged for adjustment to lift or depress the entire range of pressure exerted by the pressure applying means and also to alter the range itself.

WILLIAM C. BAXTER.
